UNITED STATES PATENT OFFICE

WILLIAM T. HORMES, OF CATONSVILLE, MARYLAND

DESIGN FOR A LEG FOR TABLES, SHOW CASES, OR THE LIKE

Application filed June 7, 1930. Serial No. 35,955. Term of patent 7 years.

To all whom it may concern:

Be it known that I, WILLIAM T. HORMES, a citizen of the United States, residing at Catonsville, in the county of Baltimore and State of Maryland, have invented a new, original, and ornamental Design for a Leg for Tables, Show Cases, or the like, of which the following is a specification, reference being had to the accompanying drawing, forming part thereof.

Figure 1 is a side elevation illustrating a leg embodying the design of the invention. Figure 2 is a transverse cross section on the line 2—2 of Figure 1. Figure 3 is a transverse cross section on the line 3—3 of Figure 1.

I claim:

The ornamental design for a leg for tables, show cases or the like, as shown.

WILLIAM T. HORMES.
